FIG. 1.

FIG. 3.

John W. Wingett,
INVENTOR
BY *Victor J. Evans*
ATTORNEY

UNITED STATES PATENT OFFICE.

JOHN W. WINGETT, OF WASHINGTON, PENNSYLVANIA.

TUBING PROTECTOR.

1,402,699.

Specification of Letters Patent. Patented Jan. 3, 1922.

Application filed May 23, 1921. Serial No. 471,913.

To all whom it may concern:

Be it known that I, JOHN W. WINGETT, a citizen of the United States, residing at Washington, in the county of Washington 5 and State of Pennsylvania, have invented new and useful Improvements in Tubing Protectors, of which the following is a specification.

This invention relates to protecting devices, and more particularly to means for protecting the tubing of oil and gas wells.

One of the main objects of the invention is to provide simple and efficient means whereby the casing head and gas line of an oil or gas well are effectively enclosed by heat insulating material so as to prevent excessive heating and igniting of the gas or oil in the event of the derrick catching fire. A further object is to provide a device of the character stated which may be quickly and easily applied. Another object is to provide a device adapted to permit ready access to the casing head when necessary. Another object is to provide a device in which heating of the upper end of the tubing and the casing is effectually prevented thus eliminating possibility of the tubing and casing becoming detached from the head and dropping into the well, such as frequently occurs where the upper end of the casing and tubing, and the casing head is subjected to great heat and is then cooled. Further objects will appear from the detailed description.

35 In the drawings:—

Figure 1 is a side view of a protector constructed in accordance with my invention as applied;

Figure 2 is a central vertical section 40 through the same;

Figure 3 is a top plan view of the lower section of the casing.

The device is intended to be used in connection with a casing head *a* of any suitable or preferred type provided in its upper face with a cylindrical recess *b* within which is supported a disc *c* having a central opening for reception of tubing *d* which is provided with a joint including a collar *e* positioned above and resting upon disc *c*. Casing *f* is threaded into the lower end of head *a* and communicates at its upper end with a gas receiving chamber *g* positioned beneath disc *c*. Gas pipes *h* communicate 55 with the chamber *g* at opposite sides thereof.

In applying the device a suitable pit is

dug beneath the derrick floor and receives a sheet metal casing *1* which extends above and below the casing head. This casing includes a cylindrical body *2* to the lower 60 end of which is attached, by pin and bayonet slot connections *3*, a bottom member or section *4*. This member is provided with two half circular bottom plates *5* each provided at the center of its straight edge with an 65 arcuate cutout *6*, these cutouts forming a circle for reception of the well casing *f*. In applying the device, after the pit has been dug to the desired depth, member *4* is placed over the casing head *a* and is moved downwardly along well casing *f* to the bottom of the pit upon which it rests. The plates *5* raise upwardly and outwardly within member *4* to accommodate passage of this member over the casing head, and drop in 70 inwardly so as to fit about well casing *f* when member *4* is below head *a*. As will be understood, member *4* is placed in position before the gas pipes *h* are threaded into the casing head. After member *4* is in position, body 75 *2* of the casing is placed in position and attached to member *4*. After this has been done the gas pipes *h* are threaded into the casing head, body *2* of the casing being provided with openings to accommodate these 80 pipes. After sections *2* and *4* of the casing have been placed in position, a top section *7* is placed about the upper portion of body *2* and forms therewith a cylindrical casing 85 extending an appreciable distance above the 90 casing head *a* and collar *e*. The casing thus produced is then filled with a mixture of water and clay, or any other suitable refractory material which, when set, forms a thick cylinder completely enclosing the 95 casing head and associated parts and extending an appreciable distance above and below the same. This mass of refractory material serves as a heat insulator which effectually prevents heating of the casing 100 head and the parts associated therewith in the event that the derrick burns down. By preventing this heating of the casing head and associated parts I eliminate possibility of the well casing or tubing becoming detached and dropping into the well in the event of burning of the derrick, such as frequently occurs in structures now commonly in use. By removing upper section *7* of the casing, the material enclosed by this section 105 may be readily removed thus permitting ready access to the upper portion 110

of the casing head, when desired or necessary.

What I claim is:—

In combination with a casing head and a well casing and tubing carried thereby, a lower member having independently movable bottom plates adapted to fit about the well casing, a body member fitting into said lower member, and an upper member fitting about the upper portion of said body member, all of said members co-operating to

form a cylindrical casing disposed concentric with the well casing and extending above and below the casing head, said cylindrical member being filled with refractory material surrounding the well casing and the tubing above the head and completely enclosing said casing head and associated parts.

In testimony whereof I affix my signature. 20

JOHN W. WINGETT.
